UNITED STATES PATENT OFFICE.

HERBERT ABRAHAM, OF NEW YORK, N. Y., ASSIGNOR TO THE RUBEROID COMPANY,
A CORPORATION OF NEW JERSEY.

ROOF COVERING.

Application filed November 7, 1921. Serial No. 513,323.

To all whom it may concern:

Be it known that I, HERBERT ABRAHAM, a citizen of the United States, residing in the city, county and State of New York, have invented certain new and useful Improvements in Roof Coverings, of which the following is a specification.

This invention relates to roof coverings made of colored slate surfaced prepared roofing shingles or strips laid in overlapping courses.

One of its objects is to provide a roofing of attractive and ornamental appearance which is obtained by laying the roof with elements of one or more colors and by tinting the exposed portions of some of the elements of each color with bituminous paint compositions of different shades of that color.

According to my invention I provide a roofing, the exposed portion of which is colored in three or more different shades, interspersed in an irregular manner, but blending to give a pleasing variegated color or tapestry effect.

The invention may also be applied to existing slate surfaced shingle roofs so as to refinish the roof and give it the desired tapestry effect.

In the accompanying drawing, forming part hereof, I have shown an indeterminate portion of a roof covering embodying my invention.

The drawing shows, in plan, a portion of a roof covering formed of elements which are laid in overlapping courses with the lower part of each element exposed to the weather. The elements may consist of individual shingles, in which case the laterally adjacent ones of each row will be spaced apart; or the elements may consist of so-called "shingle-strips" which when laid in overlapping courses simulate the appearance of individual shingles. The method of laying the elements, however, does not constitute a part of this invention and is merely described in order to illustrate an application of the invention. Furthermore, the elements used may be of any desired configuration.

Preferably, though not necessarily, all of the elements used in laying the roof will be of a single color. To impart the desired decorative effect, I apply bituminous pigment-paint compositions of different shades

of the color of the element to the exposed portions of certain thereof, selected in sparse order but so that the total quantity painted with each shade bears a proportionate relation to the whole.

For example, assuming that the roof illustrated in the drawings is laid with green slate covered individual shingles, in carrying out my invention I apply a darker shade of green bituminous paint to the exposed portions A of approximately 25% of the shingles, and a lighter shade of green bituminous paint to the exposed portions B of another 25%. The exposed portion C of the remaining shingles are left uncoated, that is in their original color. By selecting the shingles to be painted at random, but in approximately the proportions stated, I am enabled to produce a roof covering having an attractive ornamental appearance which gives a pleasing variegated color or tapestry effect.

For the purpose of tinting the elements I prefer to employ a composition of substantially the character set forth in Letters Patent No. 824,898, granted to me on July 3, 1908, but I do not necessarily limit myself to that composition as any suitable bituminous paint may be used.

What I claim is:

1. A roof covering composed of prepared roofing elements laid in overlapping courses, each element having a coating of colored grit, the exposed portions of certain of the elements having a coating of bituminous paint applied over the grit coating, the color of the bituminous paint coating being the same as that of the grit coating but of a different shade.

2. A roof covering composed of roofing elements laid in overlapping courses, each element having a coating of colored grit, the exposed portions of approximately 25% of the elements having a coating of bituminous paint applied over the grit coating, the color of the bituminous paint coating being the same as that of the grit coating but of a different shade.

3. A prepared roofing shingle having one entire surface faced with grit of a single color, and having a coating of bituminous coloring matter of a different shade from the color of the grit applied on the facing of the lower third portion of the shingle.

HERBERT ABRAHAM.
